UNITED STATES PATENT OFFICE.

GUY E. SCOTT, OF WILKINSBURG, PENNSYLVANIA, ASSIGNOR TO WESTINGHOUSE ELECTRIC & MANUFACTURING COMPANY, A CORPORATION OF PENNSYLVANIA.

INCLOSED RECEPTACLE.

Application filed April 18, 1922. Serial No. 555,106.

My invention relates to fuse receptacles and particularly to inclosed receptacles.

One object of my invention is to provide a fuse receptacle that may be placed at any desired point along a standard conduit for electrical conductors and to which a fuse may be attached or replaced without necessitating the removal of the cover.

Another object of my invention is to provide a fuse receptacle, having the above characteristics, wherein the conduit may readily be attached to the housing by means of well known standard fittings for conduits and wherein three sides of the housing are open when the cover is removed for the purpose of making the conductor terminal clamps of the fuse receptacle or clips readily accessible, thus making the device relatively easy to install.

Another object of my invention is to provide a pressed metal housing for fuses that is made in two pieces which may readily be assembled.

These and other objects, that will be made apparent throughout the further description of my invention, are attained by means of the fuse receptacle hereinafter described and illustrated in the accompanying drawings, wherein:

Figure 1 is a front view of the body or base portion of the receptacle;

Fig. 2 is a transverse section through the receptacle taken on the line II--II of Fig. 1, showing the cover in assembled relation to the base, and

Figs. 3 and 4 are front and end views of the cover, respectively.

Referring to the drawings, the apparatus includes a body or base portion 4 that is pressed from a single piece of sheet metal and is provided with two end walls 5 and 6 that are disposed at right angles to the base portion, and two marginal flanges 7 and 8 that extend toward the front of the structure.

The end walls 5 and 6 are each provided with a perforation 9 for receiving the threaded ends of standard conduits or metal housings. It will be seen that the body or base 4 is disposed between the ends of a conduit 10 and constitutes substantially a continuation thereof.

The base 4 is provided with threaded holes 13 for receiving screws 14 that serve to se-

cure a pair of plug receptacles 15 to the base. As shown, the housing is adapted for use in a two-pole circuit, in which case each receptacle is connected in the circuit in such manner that a fuse plug 16 is connected in series with a separate conductor.

The cover 17 for the housing comprises a metal plate of U-shape that is provided with integral side walls 18, the plate constituting a three-sided cover conforming in contour to the edges of the end walls 5 and 6 which the plate overlaps when in assembled relation to the base 4. The free edges of the side walls 18 fit snugly within the flanges 7 and 8 which prevent lateral displacement thereof when the cover is in assembled relation to the base.

The cover is retained in operative position by means of screws 19 that extend through perforations 21 in the cover and are threaded in the perforations 22 in the attaching ears 23 that are formed integral with the end members 5 and 6.

The cover 17 is provided with two perforations 24 that are aligned with the receptacles 15 and through which the fuse plug 16 may be inserted. As indicated in Fig. 2, the enlarged end of the standard fuse plug 16 extends exteriorly of the casing when it is in assembled relation to the fuse receptacle and may readily be turned and disengaged therefrom without necessitating removal of the cover 17.

In order to prevent the fuse from coming into contact with the cover as it is being inserted in the receptacle, an insulating plate 25, having perforations 26 aligned with the perforations 24 of the cover, is riveted to the inner face of the cover. The perforations 26 are of less diameter than those in the cover and, therefore, constitute an insulating margin for preventing engagement of the fuse and the cover.

By reason of this construction, readily accessible fuses may be located at any convenient point along the metal conductor conduit. The construction is simple and inexpensive and may be conveniently installed in any standard conduit system.

While I have described and illustrated but one embodiment of my invention, it will be apparent to those skilled in the art that various changes, modifications, substitutions, additions and omissions may be made therein

without departing from the spirit and scope of my invention, as set forth in the appended claims.

I claim as my invention:

- 5 1. A fuse receptacle comprising a metal bottom portion formed of sheet metal and having oppositely disposed integral flanges and oppositely disposed integral side portions provided with openings for receiving 10 wiring conduits, and a cover portion formed of sheet metal and having opposite integral side walls fitting within and overlapping the flanges and constituting a cover of U-shape conforming in contour to, and closely 15 fitting the edges of the walls of the bottom portion to constitute with the bottom portion a complete two-piece enclosure for the fuse devices.
2. A fuse receptacle comprising a metal 20 bottom portion formed of sheet metal and

having oppositely disposed integral flanges and oppositely disposed integral side portions provided with openings for receiving wiring conduits, and a cover portion formed of sheet metal and having opposite integral side walls fitting within and overlapping the flanges and constituting a cover of U-shape conforming in contour to, and closely fitting the edges of the walls of the bottom portion to constitute with the bottom portion a complete two-piece enclosure for the fuse devices, the said cover portion being provided with openings through which the fuse devices are accessible and which are closed by the said devices.

In testimony whereof, I have hereunto subscribed my name this 13th day of April, 1922.

GUY F. SCOTT.
